UNITED STATES PATENT OFFICE.

WILLIAM M. JENKINS, OF CHICAGO, ILLINOIS.

WALL BOARD.

Application filed September 15, 1922. Serial No. 588,462.

This invention relates in general to wall boards, or "plaster boards", adapted for use in building constructions, the present board being of the general character of that disclosed in my pending application, Serial No. 488,749, filed August 1, 1921.

One of the purposes of this invention is to provide a composition wall board having strong and durable edges which will not be liable to become chipped or cracked in handling, and which will permit the driving of nails through the board near the edges thereof without chipping or breaking the board.

Another purpose is to provide a reenforcement for the edges of the board which can be readily applied as the board is being formed, and which will greatly strengthen these edges and render the board more durable for handling and nailing.

A further object is to utilize the covering material in which the composition body is enclosed for adding to the strength and durability of the edges of the board by providing a covering of double thickness along said edges.

Still another object is to provide an improved joint or seam by which the opposed edges of the covering material may be united so as to obviate the overlapping of the opposed edges of the material and enabling the production of a smooth and even joint.

Other objects and advantages of the invention should be apparent as the same becomes better understood by reference to the following description, when considered in connection with the accompanying drawings.

Referring to the drawings:

Fig. 1 is a cross sectional view of a wall board embodying my invention; and

Fig. 2 is a similar view showing a modification.

Referring now to the drawings more in detail, reference character 11 designates the body of my improved board, which is formed of suitable composition usually comprising as its principal ingredient gypsum, which is customarily mixed with fibrous material, water and suitable set-regulating material to form a plastic mass commonly known as "stucco". This body may be formed in any approved manner, machines being customarily employed for this purpose.

In the form of the invention shown in Figs. 1 and 2, the edges of the board are reenforced with suitable fibrous material formed in sheets or strips and arranged to provide lam-

inated margins at the sides of the boards. In this instance, the outer reenforcing strip or element is bent into substantially U-shape form providing the upper and lower legs 12 and 13 united by a connecting portion 14. One of these reenforcing elements is disposed along each edge of the composition body and provides a reinforcement for the margins of both faces of the board and also for the edge face so that the board will not chip or crack along the edges when being handled and will not break or chip when nails are driven therethrough near the edges. The reenforcing element is preferably so proportioned that the outer faces of the legs 12 and 13 lie flush with the top and bottom faces of the board, as shown in Figs. 1 and 2, and while the composition may completely fill the channel of the reenforcing element as shown at the left in Fig. 1, I have found it preferable to provide a nailing area formed completely of laminated reenforcing strips, and with this end in view, there may be disposed within the channel, as illustrated at the right in Fig. 1, a series of strips 15 which lie between the portion 14 of the channel and the edges of the composition 11, as shown in Figs. 1 and 2. Nails may therefore be driven through this laminated margin of the board without any liability of cracking or chipping the board.

While the outer face of the portion 14 may be exposed and form in itself the edge face of the board as shown in Fig. 2, in which case the upper and lower faces only of the body are covered by sheets of paper or other fibrous covering material 16 and 17, further strength may be imparted to the edges of the board by completely enclosing these edges in the covering material. This result may be accomplished, as shown in Fig. 1, by making the upper and lower sheets 16 and 17 of greater width than the board so that the margins of the covering sheets may be folded to provide a double ply reenforcing enclosure along the edges of the board. As shown in Fig. 1, the upper sheet 16 is folded downwardly over the board edge as indicated at 18 and thence inwardly for any desired distance as indicated at 19. Similarly, the sheet 17 is folded upwardly as indicated at 21 over the portion 18 and thence inwardly over the body of the board, as indicated at 22. This construction provides a board which is completely enclosed in a sheath, the body of the board being reenforced along the marginal edges and the edges themselves being further

reenforced by the overlapped plies of the covering material.

Should it be desirable to use sheets of covering material narrower than the board to be formed, or if for any other purpose it should be desirable to have a joint in the sheath on one face of the board, a simple joint without overlapping edges may be formed as illustrated in Fig. 1 by disposing the opposed edges 23 and 24 of the sheath in abutting relation and positioning a strip 25 of suitable material beneath the butt joint, this strip being secured to one or both of the edges 23 and 24 by a suitable adhesive or by the plastic material forming the body 11 of the board, if preferred, in which event the strip 25 is provided with one or more rows of perforations 20 through which the plastic material of the body is extruded under pressure so as to form a bond between the opposed faces of the covering material. Similarly the channel member 12 and the upper sheet 16 may be perforated as indicated at 30 and 40 respectively to permit access of the plastic material to the under faces of the overlapped ends of the sheets for adhesive purposes.

It will be apparent from the foregoing that my invention contemplates a wall board which is strengthened and reenforced along both edges, or either, by overlapping the margins of the covering sheet or sheets or by providing a channel-shaped edge liner which may contain laminated reenforcing edge or, if preferred, both types of reenforcement may be employed so as to produce a strong and durable board.

If a single sheet instead of two sheets of

covering material is preferred the joint may be made along one edge, and formed in any of the manners disclosed, or it may be of the 40 butt joint type located between the edges of the board as shown in Fig. 1.

In any of the forms of joint disclosed, the lower ply of covering material may be provided with as many perforations as may be 45 advisable and arranged in any desired relation.

I claim:

1. A wall board, comprising a composition body provided with a reenforced margin 50 comprising a channel-shaped reenforcing element straddling the edge of said composition, and enclosing a laminated reenforcement disposed between the edge of the composition and the connecting portion of the element. 55

2. A wall board, comprising a composition body provided with a laminated edge, and a separate reenforcing element enclosing said edge and the margin of the composition.

3. A wall board, comprising a composition 60 body provided with a reinforced laminated edge, and covering material enclosing said body and forming a double ply reenforcement along the edges of the board inwardly along the face of the board a limited distance 65 from said edges.

4. A wall board, comprising a composition body provided with a laminated edge and a reinforcing element inclosing said edge and the margin of the composition body, said element being interlocked with the composition 70 of the body.

WILLIAM M. JENKINS.
